UNITED STATES PATENT OFFICE.

SAMUEL ALLEN GUIBBERSON, JR., OF SAN FRANCISCO, CALIFORNIA.

PIPE AND CASING TONGS.

1,118,604.

Specification of Letters Patent.

Patented Oct. 6, 1914.

Application filed March 7, 1914. Serial No. 823,194.

To all whom it may concern:

Be it known that I, SAMUEL ALLEN GUIBBERSON, JR., a citizen of the United States, residing in the city and county of San Francisco and State of California, have invented certain new and useful Improvements in Pipe and Casing Tongs, of which the following is a specification.

My invention relates to the class of tongs, for well-casing and other pipes.

My invention though applicable to tongs of any type in which opposing gripping jaws are alternately forced to and relieved from their work, is particularly applicable to those in which the handle has an operative connection with the rear ends of the jaws, such, for example, as the pipe and casing tongs of Letters Patent of the United States No. 934332 of September 14, 1909.

The object of my invention is both to provide for entering the tongs on the pipe from their forward ends, and to provide for a gripping and compensating action at the front as well as at the rear of the jaws. These objects I attain by a novel automatically latching joint at the front of the jaws; and my invention therefore consists in a pipe or casing tongs embodying said joint, as I shall now fully describe by reference to the accompanying drawings, in which—

Figure 1 is a side elevation, broken in part, of my tongs. Fig. 2 is a front view of the same.

1 and 2 are the opposing jaws. The operative connection at the rear ends of the jaws may be of any suitable character. The connection which I here show is that disclosed by the Patent No. 934332 above referred to.

3 is a handle having a laterally inclined head 4. The shank 1' of the jaw 1 enters the head and is pivoted therein by a bolt 5. Forward of this pivotal center, the shank 1' has fitted through it a guide pin 6 which plays in an elongated slot 7 in the head 4.

Fitted through the extremity of the head is a pin 8 upon which a slot 9 in the shank 1' of the jaw 2 plays.

In the tongs of the prior patent above mentioned, the jaws were permanently hinged together at their forward ends and in order to apply the tongs the pin 8 had to be withdrawn in order to free the jaw 2 so that it might swing open. The tongs were then applied to the pipe through the open rear connection of the jaws. Then when the

connection had been again made by the restoration of the pin 8, the handle was moved to cause the jaws to alternately grip and to release the pipe.

In the present improvement, I have what may be termed a separable, gripping joint at the front of the jaws. The separability of the joint enables the tongs to be applied to the work from the front end, and its gripping effect, not only compensates for wear at that place, but adds to the general efficiency of the tongs.

The front end of the jaw 1 is slotted out or bifurcated at 10 to form side ears between which is fitted the latch 12, said latch being carried by and pivoted upon a cross bolt 13. The latch is formed at one end with a handle 11, and at the other end with a beveled head 14 terminating in a catch shoulder 15.

The forward end of the jaw 2 is grooved out at 16 to permit the latch head to play therein, and in said groove the end is beveled or curved as at 17, terminating in a shoulder 17 with which the catch shoulder 15 coacts.

18 is a spring to control the latch 12. This spring is carried by a cross pin 19 in the slotted end of the jaw 1.

It will be seen by reference to Fig. 1, that the body of the latch 12 is formed with a curved depression or notch 20 which coacts with the pin 19 to serve as a limiting stop. To fit the tongs to the work, the handle 11 of the latch is drawn back, which movement withdraws the catch shoulder 15 of the latch head from the catch shoulder 17 of the jaw 2. The jaw 2 then falls open; and the handle 11 being then released by the operator, the spring 18 throws the latch 12 back to a position in which it is ready for action again. This position is defined by the engagement of the limiting stop notch 20 of the latch coacting with the pin 19. Thus the latch is held in position ready for use.

When the tongs are entered upon the work, the jaw 2 is pushed back to place. In this movement its curved or beveled outer end 17 contacts with the beveled head 14 of the latch 12, and forces said head back until having passed said contact, the latch springs in again and throws its catch shoulder 15 under the catch shoulder 17 of the jaw, thus automatically locking said jaw. It will now be seen that the joint thus described,

not only permits the entering of the tongs on the work from the front, without the

necessity of disturbing the operative connections at the rear, but it also presents a connection at the front sufficiently variable or elastic to provide both for a gripping effect in front, and for compensation for wear of the jaws at that place.

21 indicate biting teeth in the jaw 2.

I claim:

1. A pipe and casing tongs comprising 10 opposing jaws, a handle, a connection between the handle and the rear ends of the jaws for operating them to grip and to release the work; and an automatic latching device to lock the forward ends of the jaws, 15 consisting of a spring controlled latch pivotally carried in one jaw, and formed with a beveled catch head, the end of the other jaw being formed to receive and to engage said head.

20 2. A pipe and casing tongs comprising opposing jaws, a handle, a connection between the handle and the rear ends of the jaws for operating them to grip and to release the work; an automatic latching device to lock the forward ends of the jaws, 25 consisting of a spring controlled latch pivotally carried in one jaw, and formed with a beveled catch head, the end of the other jaw being formed to receive and to engage 30 said head; and means for automatically holding the latch in position for engagement.

3. A pipe and casing tongs comprising 35 opposing jaws, a handle, a connection between the handle and the rear ends of the jaws for operating them to grip and to release the work; an automatic latching device to lock the forward ends of the jaws, 40 consisting of a spring controlled latch pivotally carried in one jaw, and formed with a beveled catch head, the end of the other jaw being formed to receive and to engage said head; and means for automatically holding the latch in position for engagement, 45 consisting of a fixed pin carried by one of the jaws and a notch in the latch cooperating with said pin.

4. In a pipe and casing tongs, opposing jaws, one of said jaws having its forward 50 end slotted, and the other of said jaws having its forward end grooved and beveled and shouldered in said groove; in combination with a spring-controlled latch pivotally mounted in the slotted forward end of the

first jaw, said latch having a beveled catch- 55 head adapted to coact with the grooved, beveled and shouldered forward end of the second jaw to automatically lock the two jaws together.

5. In a pipe and casing tongs, opposing 60 jaws, one of said jaws having its forward end slotted, and the other of said jaws having its forward end grooved and beveled and shouldered in said groove; in combination with a spring-controlled latch pivotally 65 mounted in the slotted forward end of the first jaw, said latch having a beveled catch-head adapted to coact with the grooved, beveled and shouldered forward end of the second jaw to automatically lock the two 70 jaws together; a fixed pin in the first jaw and a notch in the latch coacting with the pin to limit the movement of the latch and to hold it in position ready for engagement.

6. A pipe and casing tongs comprising 75 opposing jaws, a handle having a laterally inclined head, connections between the handle head and the rear ends of the jaws consisting of a stationary pivot of one of said jaws with the handle head, and movable 80 pivots of both jaws with said head; and an automatic latching device at the forward ends of the jaws, consisting of a spring controlled latch pivotally carried by one of the jaws and having a catch head adapted to 85 engage and release the other jaw.

7. A pipe and casing tongs comprising 90 opposing jaws, a handle having a laterally inclined head, connections between the handle head and the rear ends of the jaws consisting of a stationary pivot of one of said jaws with the handle head, and movable 95 pivots of both jaws with said head; and an automatic latching device at the forward ends of the jaws, consisting of a spring controlled latch pivotally carried by one of the jaws and having a catch head adapted to engage and release the other jaw, and a fixed pin coacting with a notch in said latch to hold the latter ready for operation.

In testimony whereof I have signed my name to this specification in the presence of two subscribing witnesses.
